DESIGN FOR A LIFE PRESERVER

Nicholas L. De Candia, Astoria, Long Island, N. Y.

Application November 9, 1940, Serial No. 96,448

Term of patent 7 years

To all whom it may concern:

Be it known that I, Nicholas L. De Candia, a citizen of the United States of America, residing at 25-61 34th Street, Astoria, Long Island, in the county of Queens and State of New York, have invented a new, original, and ornamental Design for a Life Preserver, of which the following is a specification, reference being had to the accompanying drawing, forming a part thereof.

in dotted lines to clearly illustrate the side portions of the life preserver.

The body strap ends are not tied in Figure 2, for the purpose of better illustration of the configuration of the float members.

I claim:

The ornamental design for a life preserver, as shown.

NICHOLAS L. DE CANDIA.
